[57] CLAIM

The ornamental design for a combined wine bucket and table attachment bracket, as shown and described.

DESCRIPTION

FIG. 1 is a top front perspective view of a combined wine bucket and table attachment bracket showing the left side of my new design;

FIG. 2 is a perspective view showing the rear, top and left side thereof;

FIG. 3 is a right elevational view thereof as installed on a table;

FIG. 4 is a right elevational view thereof showing the wine bucket disengaged from the table attachment;

FIG. 5 is a front elevational view thereof;

FIG. 6 is a rear elevational view thereof taken along lines 6—6 of FIG. 4;

FIG. 7 is a top elevational view thereof with the wine bucket disengaged from the table attachment;

FIG. 8 is a bottom view thereof with the wine bucket disengaged from the table attachment; and

FIG. 9 is a left elevational view thereof with the wine bucket disengaged from the table attachment.

The broken line showing of a fragment of a table top in FIGS. 1 and 3 is for illustrative purposes only.
